(57) **CLAIM**

We claim the ornamental design for a leisure bed, as shown and described.

DESCRIPTION

FIG. 1 is a perspective view of a leisure bed.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a perspective view of a second embodiment of the leisure bed.

FIG. 8 is a front view thereof.

FIG. 9 is a rear view thereof.

FIG. 10 is a left side view thereof.

FIG. 11 is a right side view thereof.

FIG. 12 is a top view thereof.

FIG. 13 is a perspective view of a third embodiment of the leisure bed.

FIG. 14 is a front view thereof.

FIG. 15 is a rear view thereof.

FIG. 16 is a left side view thereof.

FIG. 17 is a right side view thereof.

FIG. 18 is a top view thereof.

FIG. 19 is a perspective view of a fourth embodiment of the leisure bed.

FIG. 20 is a front view thereof.

FIG. 21 is a rear view thereof.

FIG. 22 is a left side view thereof.

FIG. 23 is a right side view thereof; and,

FIG. 24 is a top view thereof.

The broken lines illustrate portions of the leisure bed that form no part of the claimed design.
